MARINE BOW LIGHT

John V. Hansen, Madison, and Ralph T. Jacobsen, Stoughton, Wis., assignors to The Electric Storage Battery Company, Philadelphia, Pa., a corporation of New Jersey

Filed May 15, 1961, Ser. No. 65,177

Term of patent 14 years

(Cl. D48—32)

FIG. 1

FIG. 2

FIG. 3

FIG. 4

FIG. 5

FIG. 1 is an enlarged front perspective view of a marine bow light, showing our new design.

FIG. 2 is a side elevation thereof.

FIG. 3 is a front elevation thereof.

FIG. 4 is a top plan view thereof.

FIG. 5 is a rear elevation thereof.

The side of this marine bow light not shown is identical to that shown.

We claim:

The ornamental design for a marine bow light, as shown and described.
